UNITED STATES PATENT OFFICE.

JOHN P. STANTON, OF DETROIT, MICHIGAN.

SUSPENSION DEVICE.

1,215,738.

Specification of Letters Patent. Patented Feb. 13, 1917.

Application filed February 12, 1916. Serial No. 77,887.

To all whom it may concern:

Be it known that I, JOHN P. STANTON, a citizen of the United States, residing at Detroit, in the county of Wayne and State of Michigan, have invented certain new and useful Improvements in Suspension Devices, of which the following is a specification.

This invention relates to suspension devices and more particularly to that class thereof which are used in supporting the bodies of vehicles on the chassis or frame, and it has for one of its objects the provision of a device of this character comprising as its essential features a pair of members which are substantially similar in form and each of which has a portion thereof extending along the other at a point substantially midway between the point of support and the point where the load is carried.

The invention has, furthermore, for its object the provision of novel means for assembling and locking a pair of spring members, each of which being preferably in the form of a "full elliptic" spring.

The invention has, furthermore, for its object the provision of a spring, composed of a pair of members each formed from flat spring sheet metal doubled back upon itself in the form of a letter V.

Further objects of the invention will hereinafter appear and be particularly defined in the claims.

The invention has been clearly illustrated in the accompanying drawings in which:—

Figure 1 is a side view of a spring embodying my invention, in its assembled and complete form.

Figs. 2 and 3 represent, respectively, the two essential spring members, *per se*.

Fig. 4 shows, on an enlarged scale, the manner in which the adjacent ends of the two spring members are doubled together and reinforced.

Figs. 5 and 6 represent, respectively, an end view and a side view of a clip used in conjunction with the interlocked portion of the spring members.

Fig. 7 shows the essential or primary members of the spring assembled and placed under load.

Fig. 8 shows a modification in the assemblage represented in Fig. 1.

Fig. 9 embodies a modification of that shown in Fig. 8, and

Fig. 10 shows the preferred form of assemblage and shape of the spring perform-

ing the same function as that illustrated in Fig. 1.

Referring first to Fig. 1 of the drawings, 60 M designates in a general way the upper member of the spring, shown also, *per se*, in Fig. 2. The lower portion of the spring is designated by M' and is also clearly illustrated in Fig. 3. It will here be seen that 65 each spring member is formed of a strip of flat spring metal bent back as at 10 and 10', respectively, thus producing a pair of leaves 11^a and 11^b on the member M and leaves 12^a and 12^b on the member M'. The free end of 70 each of the leaves 11^b, 12^b, are bent back as indicated at 11^c and 12^c, and it will be noted that the return bends 11^c and 12^c are of such size that they will fit within the return bends 10 and 10' above referred to, as can be readily understood by inspection of Fig. 7. The leaves 11^b and 12^b of the two spring members will thus come into position adjacent each other as clearly shown in Fig. 1, and, in order to hold the two spring members M 80 and M' in this assembled condition I provide a curved member 13 within each bend 11^c and 12^c, the terminals of this member being curled (see also Fig. 4) to receive pins or transverse bolts 15 the outer ends of which 85 are engaged by eyes 16 (see Fig. 6) of a clip C.

This clip comprises a main web 17 extending laterally of the spring leaves, and has at each end a pair of arms 18 between 90 which the spring leaves are disposed and which are of a length so as to bring the main web 17 to rest against the outer face of the outer bend of each spring member, so that in this manner the two members M 95 and M' are held against opening at those points, without, however, interfering in any way with the resiliency of the respective leaves of said members.

While under some conditions a spring 100 formed of the two members M and M' may be sufficient to attain the desired support, yet I prefer to employ in connection therewith a pair of "half elliptic" springs E and E' the central portions of which may be 105 secured to the central portions of the outer leaves of the spring members in any desired manner. In Fig. 1 I have represented as the load-sustaining support, a clip or bracket B while the chassis or frame F is 110 supported on top of the upper half-elliptic spring E and is secured on the central portion of a clip B'.

When the two members M and M' are

assembled in the manner shown in Fig. 7 the leaves 11^b and 12^b will be normally disposed adjacent each other for their entire length; but when load is placed upon the 5 upper leaves of the upper member M, these leaves 11^b and 12^b of the two members will assume a position substantially shown in Fig. 7 in which it will be noted that these two leaves have been slightly sprung away 10 from each other in their central portions, due to the reinforced return bends of the members whereby that portion of the spring is materially stiffened.

From the foregoing it will be understood 15 that the ends 12^c and 11^c are effective in increasing the resistance to the bending of the leaves at that point. On the other hand it will be noted that the rebound of the 20 upper and lower leaves 11^a and 12^a would have a tendency of springing away from these extensions 12^c and 11^c, and, in order to prevent this rebound and to act in the 25 capacity of a shock absorber, I provide these ends with clips 20 which may be secured firmly to the outer leaves so as to permit the inner ends 12^c and 11^c to slide therethrough to the small amount which the opening of the bend would bring forth.

Referring to Fig. 8, I have illustrated 30 means whereby the essential main springs M and M' may be held in substantially uniform horizontal position during the action of the entire spring under load, these means consisting preferably of straps 21 whereby 35 the auxiliary supporting springs 22 are connected at their free ends with the adjacent ends 23 of the main members M and M', respectively. Likewise the ends 23 are connected with reinforcing members 13 by 40 links 25, and, if desired, the said reinforcing members may also be connected with the auxiliary supporting springs 22, as shown in Fig. 8, by links 24.

Fig. 9 illustrates a modification of the 45 construction shown in Fig. 8 to the extent that the bends of the members M and M' are brought into central longitudinal alinement with the main adjacent leaves 11^b and 12^b, so that this bend will be in alinement 50 with the joint faces between these adjacent leaves. In this case I can employ links 25' of equal length to take the place of the links 24 and 25 above referred to.

Fig. 10 illustrates the preferred and 55 most simplified form of the entire spring in which the links have been entirely dispensed with and the free ends of the auxiliary leaves E and E' may also be passed through the straps or clips 20, 20', so that 60 the parts may have the necessary freedom of movement which is required under load or under rebound.

Changes may be made in the general organization, as well as in the particular construction of the members composing my im-

proved suspension device, without departing from the spirit of the invention, especially in the manner of connecting the principal components of the spring for coaction and in the formation of the means whereby said members are held together without in any way interfering with their proper spring function.

I claim:

1. A spring comprising a pair of members, each member being bent into V form substantially midway of its length to form a pair of leaves, one leaf of each member having a return bend and these same leaves being assembled to bring the return bend 75 of one member into the main bend of the other member.

2. A spring comprising a pair of members, each member being bent into V form substantially midway of its length to form 80 a pair of leaves, one leaf of each member having a return bend and these same leaves being assembled to bring the return bend of one member into the main bend of the other member, and a reinforcing device disposed 85 within the return bend.

3. A spring comprising a pair of members, each member being bent into V form substantially midway of its length to form 90 a pair of leaves, one leaf of each member having a return bend and these same leaves being assembled to bring the return bend of one member into the main bend of the other member, and means for slidably supporting each return bend on the main outer 95 leaf of the other main member.

4. A spring comprising a pair of members, each member being bent into V form substantially midway of its length to form 100 a pair of leaves, one leaf of each member having a return bend and these same leaves being assembled to bring the return bend of one member into the main bend of the other member, and a pair of auxiliary spring leaves secured to the outer leaves of 105 the main members, and means for connecting the outer ends of said auxiliary leaves with the main bends of the main members.

5. A spring comprising a pair of members, each member being bent into V form 110 substantially midway of its length to form a pair of leaves, one of said members having a return bend at the outer end of one of its leaves for receiving the middle bent portion of the other of said members.

6. A spring comprising a pair of members, each member being bent into V form substantially midway of its length to form 115 a pair of leaves, one leaf of one of said members having a return bend, the said members being assembled to position said return bend into the main bend of the other member.

7. A spring comprising a pair of members, each member being bent into V form 120

substantially midway of its length to form a pair of leaves, one leaf of each member having a return bend and these same leaves being assembled to bring the return bend of

5 one member into the main bend of the other member, and a pair of auxiliary spring leaves secured to the outer faces of the outer leaves of the main members, respectively, and clips for holding the free ends of said

auxiliary leaves in contact with the main 10 bends of the main members, respectively.

In testimony whereof I affix my signature in presence of two witnesses.

JOHN P. STANTON.
